UNITED STATES PATENT OFFICE

107,659

DESIGN FOR A STORAGE CABINET OR SIMILAR ARTICLE

Milton Price, Chicago, Ill., assignor to Arcrest Manufacturing Co., Chicago, Ill., a corporation of Illinois

Application October 20, 1937, Serial No. 72,342

Term of patent 3½ years

To all whom it may concern:

Be it known that I, Milton Price, a citizen of the United States and a resident of Chicago, county of Cook, and State of Illinois, have invented a new, original, and ornamental Design for a Storage Cabinet or Similar Article, of which the following is a specification, reference being had to the accompanying drawing, forming a part thereof, in which Fig. 1 is a perspective view of a storage cabinet or similar article, showing my new design, Fig. 2 is a detail vertical sectional view through a part of the cabinet, on an enlarged scale as taken on the line 2—2 of Fig. 1, and Fig. 3 is a detail horizontal sectional view, also on an enlarged scale, as taken on the line 3—3 of Fig. 1.

I claim:—

The ornamental design for a storage cabinet or similar article, substantially as shown.

MILTON PRICE.
